UNITED STATES PATENT OFFICE.

ARCHIBALD FRAME, OF DARVEL, SCOTLAND.

JACQUARD CARD-CUTTING MACHINE.

Application filed March 22, 1921, Serial No. 454,433, and in Great Britain April 1, 1920.

This invention relates to means for reading patterns for manipulating the punches for cutting jacquard cards for lace and other weaving.

5 An apparatus of the type to which my invention relates is illustrated in the accompanying drawings in which Figure 1 is a front elevation,

Figure 2 is a side elevation,

10 Figure 3 is a rear elevation, and

Figure 4 is a plan view of such machine, a preferred form of my improvements which will be hereafter described being shown in Figures 2, 3 and 4.

15 Figures 5 and 6 illustrate to a larger scale my improvements shown in Figures 2, 3 and 4.

Figures 7 and 8 are appended to illustrate more clearly the operation of the type of 20 apparatus to which my invention relates and

Figure 9 illustrates an improved needle which will also be hereafter described.

Referring to the drawings:—

A is the machine frame, B designates a 25 housing containing mechanism to operate the intermediate needles C (Fig. 7).

D (Figs. 2 and 8) is the cross needles and E the string or draw needles. The operation and function of said mechanism and 30 needles will now be described.

When the pattern fills the space in the point paper or vice versa the operator depresses the corresponding keys 1 (Figs. 1 and 2). Each of said depressed keys preferably move two horizontal pivoted arms 4 and 6 (Fig. 7) clear of driving bars 11 and 7 respectively.

By means of treadle or other mechanism F said driving bars are moved so as to 40 co-act with and move forward the arms which have not been depressed thereby moving forward the vertical bars 2 (Fig. 7) secured thereto. Those bars act on intermediate needles C which in turn act on the cross needles D (Fig. 8), each of which is provided with an indent in which rests a string or draw needle E.

The movement of the cross needles D bring the hooked ends of the corresponding 50 string needle E in the way or clear of the grid G (Fig. 8).

The cross and string needles are arranged in tiers within the needle box 14 (Fig. 4)

and the intermediate needles C after acting on one tier of cross needles are then moved vertically to act on the next tier, which movement is repeated until each tier has been actuated.

As shown in Figure 8, the ends of the needles E to which the strings are secured, the number of the strings depending on the number of repeats in the pattern, pass through a slotted plate I against which the right angled extremities of the string needles bear.

In one type of machine, certain details of which have been omitted in order to simplify the drawings and description of my invention, this plate I (Fig. 8) would be moved to the left, thereby permitting the needles E, which are not caught in the grid G, to move in a like direction and operate the selecting needles in the selecting needle box. Those selecting needles operate on the punches which are caught in a hand plate 75 and the cards thereafter punched in the usual manner, all as will be readily understood by those skilled in the art.

In another type of machine, the grid G (Fig. 8) would be moved to the right carrying with same the string needles E caught therein. The strings attached to the latter move short spindles clear of the punches of the punching machine. The other punches retained by the spindles make 85 the necessary punches in the card. Here again, certain constructional details have not been shown, whereby the general description of my invention may be facilitated.

It is then necessary to return the cross needles D to their inner or normal position in order that the intermediate needles C may again act on same to manipulate the punches for the next card to be punched 95 and my present invention consists of improved means for so doing, all as will appear more fully hereinafter.

According to invention, a splash board is mounted opposite the ends of the cross needles remote from the intermediate needles and by automatically actuated trip mechanism hereinafter described said board is pushed inwardly so as to return the cross needles D to their normal position. The 100 board is thereafter returned to its outer or 105

normal position so that the cross needles D may be actuated by the intermediate needles C.

Said trip mechanism is preferably actuated by the means by which the string or draw needles E are returned to their normal position. The preferred construction of trip mechanism will now be described with reference to Figures 2, 3, 4 and 5 of the annexed drawings.

A splash board 12 is slidably mounted on bolts 13 carried by the box 14 containing the cross needles D. Helical springs 13^a encircle said bolts and always tend to force the said splash board 12 outward. Carried by brackets 15 also secured to said box 14 is an upright spindle 16 to which are rigidly secured an outwardly projecting arm 17 and a number of cam or like members 18 the faces of which bear against the splash board 12.

Carried by a bracket 28 of the frame containing the slotted plate I is a pivoted arm 21, notched as at 22 and held in engagement with the end of the arm 17 by means of a spring 23. 24 is a fixed pin secured to the machine frame A.

The machine illustrated in Figures 1 to 4 is of the type in which the plate I is, by means of rods 27 (Fig. 4), moved to the left by treadle or like mechanism actuated by the operator in charge of the punching machine, thereby permitting the needles E which are not caught in the grid G to move in a like direction to operate the selecting needles in the selecting needle box. When the punches heretofore mentioned have been caught in the hand plate, the plate I (Fig. 8) is moved to the right to its normal position. The action of the trip mechanism is as follows:

When the plate I is moved to the left the notched arm overrides the end of the arm 17, being held in engagement therewith by means of the spring 23. On the return movement the notch 22 coming in contact with the arm 17 turns same and thereby also the spindle 16 and cam members 18 which latter, acting on the splash board, moves same inwardly, thereby returning the cross needles to their normal position. Before the end of the return stroke the arm 21 contacts with the pin 24 which results in the notch 22 being freed from the arm 17. This permits the splash board 12 to be moved outwards under the action of the springs 13^a so that the cross needles can be again actuated.

The chain dotted lines in Figure 5 indicate the position of the trip mechanism just before the notch 22 is freed from the arm 17 and the full lines indicate the normal position of the mechanism.

Preferably a hand lever 27^a is also rigidly secured to the spindle 16. By moving this lever as indicated by the arrow the operator

can immediately return all cross needles to their normal position should he find an error has been committed in operating the keys 1.

The mechanism indicated in Figure 6 is substantially similar to that in Figure 5 with the exception that the notched arm 22 is carried by a bracket 29 secured to the connecting rod 26. This arrangement is suitable for use in the automatic type of punching machine in which the punches are normally prevented from moving by short spindles secured to the string needles.

Said connecting rod 26 is connected to the grid G and punching machine in such manner that when it is moved to the left (the pivoted arm 21 then overriding the arm 17) the grid is moved to the right to operate the said short spindles.

After the card has been punched said rod is moved to the right returning the grid to its normal position and also causing the notch 22 to co-act with the arm 17 and thereby return the cross needles as hereinbefore described.

Also in such automatic machines of the type hereinabove set forth, I preferably provide means whereby, when a number of repeats are required to be punched, the grid G (Fig. 8) is kept in its outer position, i. e., the position in which the selecting needles permit of the required punches to operate the jacquard cards, as will be readily appreciated by those skilled in the art.

Under a preferred construction two catches 30, which are shown in dotted lines in Fig. 2, retain the grid (G) in the out position by engaging with notches in the two horizontal shafts carrying the grid which would correspond to shaft *a* and *a'* (Figs. 1, 2, 3 and 4). In the machine illustrated, such shafts are stationary but in the previously mentioned automatic type of machine, said shafts would slide in their bearings to actuate the grid G. The said catches are actuated by the operator, who, when the required number of repeats have been punched, withdraw same and thereby permits the grid G and cross needles D to return to the normal position, when the cross needles D may again be acted on by the intermediate needles C.

Instead of two catches as aforesaid a catch or catches engaging any part of the grid actuating gear may be employed.

The arm 17 is preferably provided with an extension 17^a, see Figure 2, which projects below the arm 21. The latter always rests on and is guided by said extension during its reciprocatory movement.

Preferably the cross needles D used in combination with the said trip mechanism are of an improved construction.

As shown at Figure 9 said needles are bent backwards at their outer end, the bent back portion being provided with notches *d*.

In their inner or normal position the outer notch is engaged by the slotted plate J of the needle box 14, and when moved outward by the intermediate needles the second notch thereon engages with said plate. Those notches prevent accidental displacement of the needle due to vibration or other cause.

In Figure 2 the lower cross needles are shown in the outer position and the upper needles in their inner position.

Preferably the other end of said cross needles are provided with ferrules d^1 which slide in circular holes in the plate K of the needle box and with the ends of which the intermediate needles co-act.

While I have described a certain embodiment of my invention in detail, and while I have pointed out certain of the most obvious principles and purposes thereof, I do not intend that the language employed in the following claims shall be limited to the precise features described, but I intend that the claims shall be construed to cover all combinations which are fairly included in the language thereof, when read in connection with the prior art, regardless of the details and functions mentioned in the description or illustrated in the drawings.

What I claim is:—

1. In apparatus of the type set forth, the combination with the cross needles, of mechanism for shifting said needles from their inner or normal position, a splash board for returning the needles to the normal position, and trip mechanism for actuating the board, substantially as described.

2. In apparatus of the type set forth, the combination with the string or draw needles, of cross needles operatively connected with the said draw needles, mechanism for shifting the cross needles from their normal position and thereby to shift the said draw needles, means for returning the draw needles to their normal position, a splash board for returning the cross needles to their normal position, and trip mechanism actuated by the said return means for the draw needles for actuating said splash board.

3. In apparatus of the type set forth, the combination with cross needles, of mechanism for shifting said needles from their normal position, and means for returning said needles to their normal position comprising a splash board located adjacent to the ends of the cross needles, a spring operatively associated with the splash board, a rod mounted adjacent to the splash board and having cam members and a projecting arm secured thereto, a pivoted arm adapted to engage with and to partially rotate said rod and thereby under action of the cam members to move the splash board to return the cross needles to their normal position and a fixed pin adapted to coact with and

disengage said pivoted arm, whereby the splash board is permitted under action of the said spring to return to its normal position.

4. In apparatus of the type set forth, the combination with a grid, of a series of cross needles having their ends bent and notched and adapted to engage the grid when in their respective outer and inner positions, a splash board for returning the cross needles to their normal position, and trip mechanism for operating said splash board.

5. Jacquard mechanism comprising draw needles adapted to operate spindles, cross needles operatively connected with the draw needles, a grid, a splash board, trip mechanism for returning the cross needles to normal position, and means associated with the trip mechanism for locking the grid and splash board in position, whereby a number of repeat patterns may be punched, substantially as described.

6. The combination with cross needles, of means for moving said needles, draw needles movable with said cross needles from a locked position to an unlocked position, depending upon the direction of movement of said cross needles, means for longitudinally moving the unlocked draw needles, and means for returning said draw needles and said cross needles to their original positions.

7. The combination with self-locking cross needles having normal and advanced positions, of means for selectively moving said needles from their normal position to their advanced position, draw needles having locked and unlocked positions, said draw needles being movable with said cross needles into one or the other of their positions depending upon the direction of movement of said cross needles, means for longitudinally moving the unlocked draw needles, and means for returning said draw needles and said cross needles to their original positions.

8. The combination with self-locking cross needle having normal and advanced positions, of means for selectively moving said needles from their normal position to their advanced position, draw needles having locked and unlocked positions, said draw needles being movable with said cross needles into one or the other of their positions depending upon the direction of movement of said cross needles, means for longitudinally moving the unlocked draw needles, means for returning said draw needles to their original position, and trip mechanism actuated in accordance with the return of said draw needles for moving said cross needles to their normal position.

9. The combination with a holding member, of self-locking cross needle having one end thereof provided with spaced notches adapted to successively engage said holding member, said notches determining the nor-

mal and the advanced positions of said needle, a splash board for moving said cross needles from their advanced to their normal position, and trip mechanism for operating said splash board.

10. In a machine of the type set forth, a plurality of cross needles having normal and advanced positions, a plurality of draw

needles operatively associated therewith, a grid, a splash board, trip mechanism co-operating with said splash board for moving said needles from the advanced to the normal position, and means operatively associated with the trip mechanism for locking said grid and said splash board in position.

ARCHIBALD FRAME.
